Primary Examiner—Dominic Simone**Attorney, Agent, or Firm—David L. Baker; Rhodes & Ascolillo****[57] CLAIM**

The ornamental design for a child's rocking toy, as shown and described.

DESCRIPTION

FIG. 1 is a perspective view of a child's rocking toy showing my new design therefor. The broken line drawings representing children are for purposes of illustration only and form no part of my design;

FIG. 2 is a top plan view;

FIG. 3 is one side elevational view, all side elevational views being the same; and,

FIG. 4 is a bottom plan view.
